UNITED STATES PATENT OFFICE.

WALTER J. PASINSKI, OF DETROIT, MICHIGAN, ASSIGNOR TO BURROUGHS ADDING MACHINE COMPANY, OF DETROIT, MICHIGAN, A CORPORATION OF MICHIGAN.

ADDING-MACHINE.

1,222,661.

Specification of Letters Patent. Patented Apr. 17, 1917.

Application filed August 8, 1913, Serial No. 783,703. Renewed September 13, 1918. Serial No. 119,979.

To all whom it may concern:

Be it known that I, WALTER J. PASINSKI, a citizen of the United States, residing at Detroit, in the county of Wayne and State 5 of Michigan, have invented certain new and useful Improvements in Adding-Machines, of which the following is a specification.

This invention relates to the type of adding machines shown in prior Patents Nos. 10 1,016,501 and 1,023,168 issued February 6, 1912, and April 16, 1912, respectively. In these machines the turning of wheels to effect registration is done by return of spring-actuated levers after displacement 15 thereof by depressible keys and release of the latter. The keys are arranged in rows each row made up of nine keys numbered from 1 to 9 and constructed and arranged to act upon the associated registering lever 20 at varying distances from its pivot, the 9-key acting nearest the pivot the 8-key a step farther away and so on. Upon reference to said prior patents it will be observed that the acting lugs of the keys are not normally 25 in engagement with the lever, the latter being stopped in its return movement by contact of its forward end with a cross bar, and it will further be observed that the lugs of the lower denomination keys 1 and 2 are 30 spaced farther from the lever than the lugs of other keys. This is so because of a purpose to arrange for uniform "dip" or extent of depression of all of the keys while at the same time preserving a compact arrangement 35 of the keys with their tops spaced slightly and uniformly from each other from front to rear. The keys are normally upheld by comparatively light springs and it has been found that, owing to the relatively slight resistance to depression of the lower denomination keys prior to their 40 striking the lever, there may be a failure to fully depress these keys against the considerably greater resistance offered by the relatively strong spring which upholds the 45 lever. The lost motion between the lugs of the other keys and the lever is so slight that the variation in resistance to their depression does not have to be taken into 50 account, the extent of their depression

against the lighter resistance being so very short that the sensation is that of applying finger pressure against the heavier resistance from the beginning. In case of the lower denomination keys however the extent of depression against the lighter resistance is of such extent as to be distinctly noticeable so that there is an inclination to relax the pressure when the heavier resistance is encountered.

The purpose of the present invention is to compensate for this greater extent of movement of the lower denomination keys against the light resistance so that there will be no noticeable increase in resistance such as to incline the operator to relax the finger pressure, and to accomplish this without introducing any additional springs into the machine, in which respect my invention differs from the prior invention of Roy L. 70 Burd constituting the subject matter of application filed August 8, 1913, Serial No. 783,701.

In the form of embodiment of my invention here shown, I accomplish the desired 75 result by interposing between the lower denomination keys and the registering lever other levers which are in direct engagement with the lugs of the key stems and which have a shifting contact or engagement with the registering lever so that displacement of the latter is in reduced ratio to the depression of the keys.

Of the accompanying drawings which 85 form a part of this specification, Figure 1 illustrates in sectionalized right-side elevation a machine of the type shown in said prior patents, having embodied therein parts for carrying out my present invention; Fig. 2 is a similar view showing one of the 90 keys depressed; and Fig. 3 is a horizontal section taken substantially on the line 3—3 of Fig. 1.

Reference may be had to the aforesaid prior patents for an understanding of the 95 machine proper in all of its details, and it will suffice to designate a few of the familiar parts of said machine with which the parts introduced for carrying out my invention are more intimately associated.

106

designates the stems of a row of keys which stems are formed with lugs d^2 extending above the registering lever F, the latter being upheld by a spring F² in contact at its forward end with a frame cross rod a^4 and the keys being normally upheld by lighter springs d surrounding reduced lower portions of the stems as heretofore. The relation between the lugs d^2 and the registering lever is the same as heretofore in which connection it is to be especially noted that the lugs of the 1 and 2-keys are spaced appreciably farther from the upper edge of the lever than are the lugs of the other keys. The key stems are slotted longitudinally as usual and frame cross rods a extend through the slots and limit the descent of the keys.

In carrying out the present invention, I pivot upon the cross rod a, which guides and limits the 2-key, an irregular-shaped lever 10 which extends forward from its said pivot and embraces the lug d^2 of the 1-key and at an intermediate point engages the registering lever F. I similarly pivot upon the frame cross rod a, which guides and limits movement of the 3-key, a similar lever 10^a which extends forward and embraces the lug d^2 of the 2-key and at an intermediate point engages the registering lever F. These two irregular-shaped levers are of substantially the same shape and specific description of one of them in this connection will suffice. Referring to Fig. 3, it will be seen that the rear portion of the lever 10 runs behind or to the left of the stem of the 2-key where said lever pivots upon the rod a, and that there is an angular portion 10^b which connects said rear portion with a forward portion extending in front or to the right of the 1-key. This forward portion which is thus offset with relation to the rear portion takes the form of a hook 10^c which extends under the lug d^2 and beyond the same and then upwardly and rearwardly above said lug, as shown in Figs. 1 and 2, with sufficient looseness to permit turning of the hook about the lug. A short rearwardly-projecting branch 10^d of the lever adjacent the central portion 10^b supports a stud on which is mounted a roller 10^e the latter engaging the upper edge of the lever F.

It will be seen that with the above-described construction the lower denomination key has its lug constantly engaged with the hook of the intermediate lever so that the latter moves at all times with the key. It will furthermore be observed that though depression of the key results immediately in displacing the lever F, the disposition of the intermediate lever is such and the relation between the roller 10^e and the lever F is such that the latter is not displaced proportionately to the depression of the

key but that the ratio of displacement of the lever is reduced. This is of course owing to the shifting engagement of the intermediate lever with the lever F, the roller 10^e traveling along the edge of the lever as the key is depressed so that part of the key depression is taken up in the swinging of the intermediate lever, and the displacement of the lever F is correspondingly lessened as compared with what the extent of displacement would be if the lug acted directly upon the lever F in depression of the key.

It will be apparent that the above-described construction provides a simple and efficient means for accomplishing the purpose of my invention. At the same time it must be understood that the invention is not necessarily limited to the particular form of embodiment here shown, but is susceptible of embodiment in other forms.

I claim:

1. In a machine of the class described the combination of a registering lever; a series of keys constructed and arranged to act upon said lever at increasing distances from the latter's pivot; and means interposed between said lever and certain keys which act at the greater distances said means serving to impart movement to the lever though creating lost motion whereby displacement of the lever accompanying movement of said certain keys is reduced as related to the key-movement.

2. In a machine of the class described the combination of a registering lever; a series of keys constructed and arranged to act upon said lever at increasing distances from the latter's pivot; and means interposed between said lever and certain keys which act at the greater distances said means serving to impart movement to the lever though effecting conversion of motion whereby displacement of the lever accompanying movement of said certain keys is reduced as related to the key-movement.

3. In a machine of the class described the combination of a spring-held registering lever; a series of depressible spring-upheld keys to act upon said lever at increasing distances from its pivot; and a lever through the medium of which a certain key acting at the greater distance displaces the registering lever.

4. In a machine of the class described the combination of a spring-held registering lever; a series of depressible spring-upheld keys to act upon said lever at increasing distances from its pivot; and a lever through the medium of which a certain key acting at the greater distance displaces the registering lever through shifting engagement therewith.

5. In a machine of the class described the combination of a spring-held registering

lever; a series of depressible spring-upheld keys to act upon said lever at increasing distances from its pivot; and a lever pivoted at one end, in engagement at the opposite 5 end with a certain key acting at the greater distance from the pivot of the registering lever, and having a shifting engagement intermediate its ends with said registering lever.

WALTER J. PASINSKI.
